UNITED STATES PATENT OFFICE.

EDWARD PARKER, OF BRISTOL, ENGLAND.

MACHINE FOR FORMING PAPER CAPSULES AND AFFIXING THE SAME TO BOTTLES.

1,070,839.

Specification of Letters Patent. Patented Aug. 19, 1913.

Application filed November 11, 1912. Serial No. 730,739.

To all whom it may concern:

Be it known that I, EDWARD PARKER, a subject of the King of Great Britain and Ireland, residing at Bristol, Kingdom of Great Britain, have invented certain new and useful Improvements in Machines for Forming Paper Capsules and Affixing the Same to Bottles; and I do hereby declare the following to be a full, clear, and exact 10 description of the invention, such as will enable others skilled in the art to which it appertains to make and use the same.

This invention relates to machines for plaiting paper capsules for bottles, jars 15 and the like, and for applying the capsules to the same, and securing the capsules thereon.

This invention has for its object to provide an improved construction of machine 20 for the said purposes.

A capsuling machine in accordance with this invention comprises the combination of means for picking up the capsuling blanks, for conveying them to and depositing them on the male die, for bringing the female die to press on the blanks and shaping them, and for carrying them and depositing them on to the bottles, jars, and like vessels, conveying the bottles and the 25 like in regular succession to the gumming brushes and thence to the capping stick, operating the capping stick for closing in the capsules about the necks of the bottles and the like, and applying and winding 30 string about the capsules.

It is to be understood that no claim is made to the elements separately of the machine set out herein.

For simplification in description the machine will be described as for dealing with bottles. In its application to jars and other vessels the construction and operation is the same as for bottles except that the dies are of different shapes to suit the other vessels, the mechanism being modified to meet the required conditions.

Referring to the drawings accompanying this specification: Figure 1 is a side elevation; Fig. 2 a plan, and Fig. 3 a longitudinal section on the line *a*—*a*, Fig. 2. Fig. 4 is an end view of the arrangement of the gumming brushes for gumming the corks or bottle stoppers and part of the bottle neck. Fig. 5 is an end view of the arrangement for closing in the capsules on the

bottles by the capping stick. Fig. 6 is a plan and Fig. 7 a side elevation of the means for putting the string around the capsules after they have been stuck on the bottles. Figs. 6 and 7 are drawn to an 60 exaggerated scale.

My improved machine is constructed and arranged and made to operate as follows:

Supported in standards 1, mounted on the fixed table 2 of the machine, is a slide 3 65 which carries two plungers 4 and 6 which are adapted to reciprocate vertically in sockets provided for them in the slide 3. By the plunger 4 the blank capsules, which are circular disks of paper and are arranged in 70 a pile 5 in a suitable receptacle on the machine table 2, are picked up one by one by pneumatic action. The plunger 6 carries the female die 7. The male die 8 is secured on the table 2. The horizontally reciprocating 75 slide 3 is operated by means of the cam 9, centered on the driving shaft 10, operating through the pivotal rocking lever 11. Arranged over the slide 3 is a crosshead 12 attached to rods 13 which are adapted to reciprocate vertically carrying the crosshead 12 with them. The crosshead 12 is operated by means of the cam 14 acting through the anti-friction roller 15 and the lever 16 pivoted 80 at 17 to the machine frame 18.

Below the fixed table 2 of the machine is a rotary carrier 19 with brackets 19^a to which are secured holders 20 for the bottles. This carrier 19, which is centered on the vertical axis 21, has intermittent motion imparted to it by means of the ratchet wheel 22 and pawl 23, the wheel being operated by the cam 24, centered on the driving shaft 10, acting through the connecting rod 25 and crank 26. The rotation of the carrier 19 is 95 always in the same direction indicated by the arrow A, Fig. 2.

The bottles are advanced in the machine by the rotary carrier 19 and each in succession is presented first to gumming brushes 100 27 and 28—see Figs. 2 and 4—which are carried by a rotary spindle 29 mounted in a frame 30 standing on the fixed table 2 of the machine and carrying a tank 31 containing the adhesive which is taken up by 105 contact of the brushes 27 and 28 with the perforated nozzle 32 as the said brushes are carried around. The spindle 29 is rotated from the driving shaft 10 through pulleys 33 and 34, Fig. 2. After application of the ad- 110

hesive the bottle is conveyed around to the plunger 6 which, as aforesaid, carries the female die 7 which, when the bottle is presented under it, is in the raised position and 5 holds the plaited capsule.

Conveyance from the pile 5 of the blank capsules and plaiting them is as follows: When the slide 3 is at the limit of its outstroke, that is to say, in the direction of the arrow B, Figs. 2 and 3, the picking-up plunger 4 is directly over the pile 5 of the blanks, and the plunger 6 with the female die 7 is directly over the male die 8. The crosshead 12 is depressed by the action of the cam 14 and the picking-up plunger 4 10 sucks up by pneumatic action the topmost blank of the pile 5. A pneumatic tube 35 attached to an air pump worked off the driving shaft 10 (the pump is not shown in the drawings) communicates with a central passage 36 in the plunger 4 and with a central passage 37 in the plunger 6. The topmost blank of the pile 5 having been thus picked up, the crosshead 12 rises. The slide 3 is, 15 by the action of the cam 9 and rocking arm 11, which is pivotal at 11^a, now advanced on its instroke and the plunger 4 is brought over the male die 8 on which it now descends. By pneumatic action the blank is 20 freed from the plunger 4. It is held on the male die 8 by pneumatic action acting through the tube 8^a which is connected to the air pump aforesaid. (The blank which was last previously deposited on the male die has now been applied by the plunger 6 25 to a bottle.) The crosshead 12 rises after the aforesaid blank has been secured by the pneumatic action on the male die 8. The slide 3 now returns on its outstroke and the plunger 4 is brought back to position 30 directly over the pile 5 of blanks. The plunger 6 now stands over the blank which was last left by the plunger 4 on the male die. In the next descent of the crosshead 12 the plunger 6 descends on the blank remaining 35 on the male die 8 and completes it. The female die 7 picks up the capsule by pneumatic action and in the next instroke movement of the slide 3 the plunger 6 carries the capsule to the position for application to the bottle, which having, as above described, 40 been gummed, is presented below the plunger 6 in time to receive the capsule from the female die 7, release of the capsule from which is effected pneumatically. The capsule adheres to the cork or stopper of the bottle. When the machine is producing 45 plaited capsules the dies 7 and 8 are fluted. For the production of unplaited capsules 50 plain dies are used. The shape of the blanks and the character of the dies will vary with the kind of capsule required to be turned out by the machine. Each bottle having, in turn, received its capsule from the die 7, is 55 conveyed around by the rotary carrier 19 to

position below the capping cup 38 which is an inverted cup hollowed out conically and which with its vertical stem 39 is termed the "capping stick". The capping stick is reciprocated vertically by the cam 40 which is centered on the driving shaft 10 and acts through the projection 40^a, the anti-friction roller 41, vertically reciprocating rod 42, and the horizontal rod 43 connected to the stem 39, by the link 44, of the capping stick 70 cup 38. The arrangement is such that when a bottle is presented under the capping stick cup 38 the stick descends and so closes in the capsule around the bottle neck. The stem 39 of the capping stick reciprocates in 75 sockets provided for it in the bracket 45 which is bolted on the table 2. Centered on the stem 39 is a pinion 46 which gears with a quadrantal rack 47 which is fixed on a spindle 48 which, at the lower end, is supported in a step bearing 49 provided on the plate 50. The spindle 48 passes through bearings in the bracket 45. The rack 47 is oscillated by means of the cam 40 operating through the anti-friction roller 51, pivotal 80 arm 52, connecting rod 53 and link 54. The purpose of the rack 47 and pinion 46 on the capping stick is to rotate the bottles about their own axes and thus to wind string or other suitable binding material, either in 85 string or band form, around each capsule immediately after the capping cup 38 has been lowered on to the bottle neck. The string is drawn from a reel or spool through a vessel containing varnish or other suitable adhesive and is led to the capping stick 90 95 cup 38 and passed under a gripper 55 which is fixed on a spindle 56 which extends parallel with the axis of the cup 38. A spring 57 coiled around the spindle 56 tends constantly 100 to hold the gripper 55 pressed toward the cup 38. At its upper end the spindle 56 has fixed to it a lever 58. On the top of the cup 38 of the capping stick is an arm 59 hinged in a bracket 60. A spring 61 acts on the arm 59 keeping the latter always in contact with the lever 58. A lug 62 is fixed on the bracket 45—see Figs. 1 and 6. In the descent of the capping stick, the arm 59, on 105 reaching the end of its downward travel strikes the lug 62 and the gripper 55 is closed in on the string against the resistance of the spring 57, and the string is accordingly gripped between the gripper 55 and the cup 38. By the action of the quadrantal 110 rack 47 the bottle is rotated and the string is wound around the capsule about the neck of the bottle. The string is severed by an adjustable knife 63 connected to the rack 47 and after the severance of the string a 115 lug 64 presses against the lever 58 and thus the spindle 56 is turned so as to open out the gripper 55 thus releasing the cut-off length of string. The string wound on the capsule sticks thereto and upon itself. The arm 59 120 125 130

then keeps the gripper open until the next bottle is presented for stringing or banding.

The arrangement of the mechanism to perform the several operations is such, and 5 the actions are so timed, that as one bottle is being gummed, another is having a capsule applied to it from the female die and another is being capped and strung or banded.

What I claim as my invention and desire 10 to secure by Letters Patent is:—

1. In a capsuling machine, the combination of a frame; a bottle carrier rotatably mounted on the frame; means for imparting intermittent motion to said carrier; means 15 for applying an adhesive to the bottle necks comprising a rotatable spindle, brushes carried by said spindle, an adhesive supply tank, and an adhesive feeding nozzle on the tank adapted to be engaged by the rotatable 20 brushes; and means for applying and affixing the capsules to the bottle necks, substantially as described.

2. In a capsuling machine, the combination of a frame; a bottle carrier rotatably 25 mounted on the frame; means for imparting intermittent motion to said carrier; means for forming and applying the capsules to the bottle necks comprising a receptacle for holding blanks, a carrier, means for reciprocating 30 and raising and lowering said carrier, a stationary die, a member on the reciprocating carrier adapted to pick up and transfer one by one the blanks from the receptacle to the stationary die, and a die carried by the 35 reciprocating member coöperable with the stationary die to form the capsule, and adapted to apply the same to the bottle necks; and means for affixing the applied capsules to the bottle necks, substantially as 40 described.

3. In a capsuling machine, the combination of a frame; a bottle carrier rotatably mounted on the frame; means for imparting intermittent motion to said carrier; means 45 for applying capsules to the bottle necks; and means for affixing the applied capsules comprising a cup adapted to fit over the bottle neck with applied capsule, a gearing for imparting rotation to said cup whereby 50 to rotate the bottle, and means associated with said rotatable cup for tying the capsule to the bottle neck with string, substantially as described.

4. In a capsuling machine, the combination of a frame; a bottle carrier rotatably mounted on the frame; means for imparting intermittent motion to said carrier; means for applying capsules to the bottle necks; and means for affixing the applied 55 capsules comprising a spindle, a cup mounted on the spindle, means for moving the spindle to bring the cup into and out of en-

gagement with the bottle necks with applied capsules, a pinion on the spindle, a 65 quadrant rack meshing with said pinion and adapted to rotate the bottle engaged by said cup; and means associated with said rotatable cup for tying the capsule to the bottle neck with string, substantially as described. 70

5. In a capsuling machine, a frame, a table mounted on the frame, a rotary carrier mounted on the frame below the table, means for intermittently rotating said carrier, bottle holders on said carrier, gumming brushes 75 mounted on a spindle disposed on the table and adapted to engage successively the neck of each bottle as the carrier rotates, means for supplying adhesive to the brushes, a male die mounted on the table, a pipe leading from the die and adapted to connect with an air pump, a receptacle for capsule blanks, guide standards on the table, a horizontal slide mounted in said guide standards disposed over the male die and receptacle, means for reciprocating said horizontal slide, plungers mounted in said slide, means for vertically reciprocating said plungers, a female die on one of said plungers, and pipes in said plungers adapted to 80 connect with an air pump. 85

6. In a capsuling machine, a frame, a table mounted on the frame, a rotary carrier mounted on the frame below the table, means for intermittently rotating said carrier, 95 bottle holders on said carrier, gumming brushes mounted on a spindle disposed on the table and adapted to engage successively the neck of each bottle as the carrier rotates, means for supplying adhesive to the brushes, 100 a male die mounted on the table, a pipe leading from the die to an air pump, a receptacle for capsule blanks, guide standards on the table, a horizontal slide mounted in said guide standards disposed over the male die 105 and receptacle, means for reciprocating said horizontal slide, plungers mounted in said slide, means for vertically reciprocating said plungers, a female die on one of said plungers, pipes in said plungers adapted to connect with an air pump, a bracket on the frame, a capping stick mounted in said bracket, a cup mounted on the capping stick, means for vertically reciprocating and rotating said capping stick and cup, a string- 110 gripping device secured on the cup, means for supplying string to the gripper, and means for opening and closing the gripping device and for cutting the string. 115

In testimony whereof, I affix my signature, in presence of two witnesses.

EDWARD PARKER.
